(57) **CLAIM**

The ornamental design for a LED display, as shown and described.

DESCRIPTION

FIG. 1 is a front, right and bottom perspective view of a LED display, showing our new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

FIG. 12 is an enlarged view of portion 12 shown in FIG. 1; and,

FIG. 13 is an enlarged view of portion 13 shown in FIG. 1.

The dot-dash broken lines depict the boundaries of the
enlargements that form no part of the claimed design.

1 Claim, 13 Drawing Sheets
